UNITED STATES PATENT OFFICE.

JOHN W. DARLEY, JR., OF BALTIMORE, MARYLAND.

AUTOMATIC GRAND PIANO.

No. 859,187.

Specification of Letters Patent.

Patented July 2, 1907.

Application filed January 12, 1907. Serial No. 351,989.

To all whom it may concern:

Be it known that I, JOHN W. DARLEY, Jr., a citizen of the United States, residing at Baltimore city, in the State of Maryland, have invented certain new and useful Improvements in Automatic Grand Pianos; and I do hereby declare the following to be a full, clear, and exact description of the invention, such as will enable others skilled in the art to which it appertains to make and use the same.

10 My invention relates to improvements in automatic grand pianos, and the object of my invention is to produce a piano of this class in which the keys may be operated either by hand or by pneumatic means, in which the front of the keys will not be moved by the operation 15 of the pneumatic means and in which the keys are never locked, but can always be played by hand, so that a duet can be played with the roll music and by hand at the same time, and so that the keys will remain stationary during the operation of the pneumatic 20 means.

With these objects in view, my invention consists in the construction and combinations of parts as hereinafter described and claimed.

In the accompanying drawings Figure 1 is a cross section of the front of a grand piano, showing my invention applied thereto, parts being shown in elevation and certain parts being omitted, as they are either well known in the art or else covered by prior applications; Fig. 2 is a front view of the same showing the fall board folded back and the music rest removed; the motor shown in Fig. 1 being omitted in this figure; Fig. 3 is a fragmentary view of the part of the gearing between the motor and the winding rolls; and Fig. 4 is an enlarged detail in cross-section of part of the roll driving mechanism.

45 a represents the supporting legs, b the lyre, c the key bottom, d the key frame, e the pneumatic box, f and g the hinged folding lid, h a wooden partition covering the tracker pipes, i, j the winding roll, k the tracker board, l the string frame, m the strings, n the dampers, o the sounding board, p the main part of the action, and q the motor, all of these parts being of the usual or well known construction.

40 r represents one of the keys pivoted at s in the usual manner to the key frame. The rear part of each of the keys r is cut away as shown in Fig. 1, and in the cut away portion is mounted a pin t, which is provided with an enlarged head u, to which is pivoted the forked end of a lever v, which carries the usual back check 45 w. The lever v is provided near its rear end with a pin x, shown partly in dotted lines in Fig. 1, which pin works in a cloth-lined slot y in the main part of the rear end of the key r thereby guiding the movement of the lever v. This lever v is arranged to lift the dampers n by means of the connections 1 and 2, in the usual way, whether it is operated by the key r or by the pneumatic

means. Preferably a pad, such as 3, is interposed between the main part of the key r and the lever v. This lever is, therefore, carried bodily by the key, the pad 3 limiting its downward movement while it is free to move upward, as it is pivoted to the head u of the pin t.

50 Mounted in the lever v between the fulcrum and the pad is the capstan screw 4, which can be screwed up and down in the usual way, a recess 5 being provided in the main body of the key r to provide a clearance for the downwardly projecting end of the capstan screw. This capstan screw is adapted to strike against the lower part of the piano action p whenever the lever v is lifted.

55 It is obvious from the construction described that a blow on the front part of the key r will lift the lever v thereby lifting the damper n and the piano action p, causing the hammer to strike against the strings. It is also obvious that if the lever v is lifted by pneumatic means, the front part of the key r will be unaffected, but the damper will be lifted and the string struck by the hammer of the piano action. The levers v are operated by pneumatic means from the pneumatic box e in the usual way. Furthermore, the levers v being pivoted at their front ends and having 60 capstan screws in the rear of said pivots, there is always a downward pressure upon said levers v thus keeping them constantly in connection with the pneumatic means, and having a tendency to press said levers against their bearings in the heads u, and thus keep 65 the rear ends of said keys always down against the cushions 6. Thus it will be seen that the keys r are never locked, hence they can always be played by hand. It will also be seen that the levers v can be operated independently of the keys by the pneumatic 70 means, or by the keys themselves when they are struck by the performer. Thus it is possible either to use the keys in the ordinary way or to use the piano to play roll music, or a player can use the roll music and play a duet therewith on the keys. The keys r 75 are never operated by the pneumatic means, which is a desirable feature in pianos of this construction.

75 7 represents the fall board, which is made larger than usual near its lower end, and is provided with the usual pivots 8 and 9 about which it rotates. This fall 80 board is cut away as shown at 10, in Fig. 2, and in dotted lines in Fig. 1, for the reception of the music roll.

85 11 represents a shaft on the projecting end of which one end of the music roll is supported, said shaft being provided with a cut-away portion in which the winged 90 end of the music roll pivot bearing is received in the usual way. 12 represents a spring pressed socket for the reception of the pivot bearing on the other end of the music roll, which parts operate in the usual manner. The shaft 11 extends through a hole provided in 95 the fall board nearly to the left hand side of the piano, and on the end of said shaft is provided a spur wheel

13, shown in dotted lines in Fig. 1. This spur wheel meshes with a similar spur wheel 14 mounted on the pivot 9.

The motor *q* by means of a sprocket chain 15 drives the shaft 16 by means of a pulley 17 thereon. Shaft 16 is mounted in brackets depending from the key bottom, and this shaft is arranged not only to rotate in said brackets, but also so that it can be shifted longitudinally therein. Loosely mounted on flanged sleeve 10 surrounding the shaft 16 are the sprocket wheels 18 and 19, which wheels are used to drive the music roll and winding roll. Each of these wheels 18 and 19 has a projection, such as 20, on its inside face, and the shaft 16 is provided with a projecting pin 21 adapted to engage either one of said pins on the wheels 18 and 19 according as the shaft is shifted to the right or to the left.

From the sprocket wheel 18 runs a sprocket chain 22, which passes over the sprocket wheel 23. Parallel 20 to the sprocket wheel 23 is a large gear wheel 24. The wheels 23 and 24 are rigidly mounted on a sleeve which is revolutely supported on a screw stud 25 secured in the frame of the piano. The gear wheel 24 is arranged to mesh with the gear wheel 14 carried by the fall 25 board. Hence it is evident, since the wheel 14 is concentric with the pivot of the fall board, that this fall board may be raised and lowered without disturbing the gear connection. The fall board is extended outwards forming a bulb, as shown at 26, the left hand 30 end of which forms a shield for the gear wheel 14, the keys *r* being cut away, as shown in Fig. 1, to provide space for said bulb-like extension.

From the sprocket wheel 19 runs a sprocket chain 27, which gears with a sprocket wheel 28. Parallel 35 to the sprocket wheel 28 is a gear wheel 30, both being rigidly secured on a sleeve supported on the screw stud 29, which is secured in the piano frame. Gear wheel 30 meshes with a gear wheel 31 on the shaft 32 of the winding roll *j*, which is mounted in a box hinged 40 as shown at 33 to the sides of the piano. This box, therefore, may be folded back in order to obtain access to the strings *m* to tune them, the gear wheels 30 and 31 simply separating during this folding back action, and meeting when the box is folded forward into the 45 position shown in Fig. 1.

k represents the tracker board over which the sheet of music passes from the music roll to the winding roll. The tracker board is ordinarily concealed by a cover 38 hinged at 34 to the top of the box 35, and when it 50 is folded upward it comes in line with the partition 36 forming a music rest, a ledge 37 serving to support the lower end of the sheet of music.

Having thus described my invention, what I claim as new and desire to secure by Letters Patent of the United States is—

1. In an automatic grand piano, the combination with 55 keys, a lever pivoted to the rear part of each key, each of said levers being provided with a back check, and connections whereby the operation of pneumatic devices will operate said lever independently of said key, whereby said levers may be operated by the movement of the keys by the player or by the pneumatic means, substantially as described.

2. In an automatic grand piano, the combination of 60 keys, a lever pivoted on the rear part of each of said keys, dampers and means whereby the action of pneumatic devices will lift the corresponding levers and thereby the dampers from contact with the strings substantially as described.

3. In an automatic grand piano, the combination of 70 keys, and a lever pivoted on the rear part of each of said keys, said lever being provided with means for operating the piano action, for checking the hammers on their return and for lifting the dampers, substantially as described.

4. In an automatic grand piano, the combination of 75 keys, a lever pivoted to the rear portion of each of said keys, said lever being provided with means whereby upon the actuation of the key the piano action is moved, the return action of the hammer is checked, and the corresponding damper lifted from the string, substantially as 80 described.

5. In an automatic grand piano, the combination of 85 keys, a lever pivoted to the rear part of each of said keys, each of said levers being provided with means whereby, upon the action of an appropriate pneumatic device, the piano action is moved, the return of the hammer is checked, and the damper is lifted for the corresponding string, substantially as described.

6. In an automatic piano, the combination of pneumatic 90 means for operating the string striking mechanism a horizontal frame provided with strings, mechanism for striking each of said strings, keys for operating said mechanism, and connections whereby said mechanism is operated by the pneumatic means, said connections being so arranged that when the pneumatic means is operating said mechanism, said keys are pressed into unoperated position, substantially as described.

7. In an automatic piano, the combination of pneumatic 100 means for operating the string striking mechanism a horizontal frame provided with strings, mechanism for striking each of said strings separately, said mechanism being located below said string frame, keys located below said mechanism, and connections whereby said mechanism may be either operated directly by said keys or by pneumatic means, the parts being so arranged that when the mechanism is operated by the pneumatic means, the rear end of said keys is pressed down into the unoperated position, substantially as described.

In testimony whereof, I affix my signature, in presence 110 of two witnesses.
